SNAP SWITCH

Christian Aalborg, Springfield, Mass., assignor to
Westinghouse Electric & Manufacturing Company,
East Pittsburgh, Pa., a corporation of
Pennsylvania

Application October 21, 1936, Serial No. 106,785

6 Claims. (Cl. 200—66)

My invention relates generally to switch mechanisms and is directed more particularly to switch mechanisms in which movement of an operating member causes a blade of the switch to be rotated over a series of stationary switch contacts with a snap action.

An object of the invention is to provide an improved switch mechanism of this general type.

Another object of the invention is to provide an improved switch mechanism of the snap-acting type which is of simple and rugged construction, which requires a minimum number of parts, and which can be manufactured at a relatively low cost.

15. The novel features that I consider characteristic of my invention are set forth with particularity in the appended claims. The invention itself, however, both as to structure and operation, together with additional objects and advantages 20 thereof, will best be understood from the following detailed description of a specific embodiment when read in connection with the accompanying drawing, in which:

Figure 1 is a plan view of a snap switch embodying the features of my invention with the operating member thereof removed;

Fig. 2 is a vertical sectional view of the snap switch illustrated in Fig. 1 with the operating member mounted in position thereon, taken on 30 the line II—II of Fig. 1;

Fig. 3 is a top plan view of the operating member for the snap switch illustrated in Figs. 1 and 2; and

Fig. 4 is a front elevational view of the operating member illustrated in Fig. 3.

Referring now to the drawing, the structure of the snap switch embodying the features of my invention consists in general of a base 5, a plurality of stationary contacts 7, a notched latch plate 9, a switch blade 11, an actuating spring 13, and a manually controlled operating member 15.

The base 5, which is constructed of suitable insulating material, has disposed in openings therein a plurality of spaced contacts 7 arranged in an arc of a circle. Each contact is provided with a terminal connector 17, which has an opening provided therein for receiving a reduced portion 19 of the contact member 7. The contact members and terminal connectors are each secured to the base by means of the reduced portion 19 thereof which passes through the opening provided in the base, and has its end portion spun over against a washer 21 positioned between the end of the reduced portion and the base. Each terminal connector 17 is provided with a pair of clamp por-

tions, one clamp portion 23 adapted to receive a conductor wire 25, and the other portion 27 adapted to receive the insulation 29 surrounding the wire.

A spindle 31 is mounted on the base approximately at the center of the arc of the circle along which the contacts are mounted. The spindle is provided with a reduced portion 33 which passes through an opening provided in the base, and has its end spun over against a washer 35 on the under side of the base. The latch plate 9 is provided with an opening for receiving the reduced portion 33 of the spindle 31, so that the latch plate is held in rigid position between the shoulder on the spindle and the base 5. The latch plate 9 has a segmental portion 37 provided with a flange 39. The flange 39 has a plurality of spaced notches 41, one for each contact. Each notch is located at a point diametrically opposite its corresponding stationary contact. The latch plate 9 has an extension 43 provided with an opening at the end thereof for receiving a terminal stud 45. The terminal stud passes through a terminal connector 47 similar to the connectors 17. The terminal connector 47 is adapted to receive a live conductor 49 provided with an insulating sheath 51.

The terminal connector 47, terminal stud 45, and extension 43 constitute a means for conducting current from the live conductor 49 to a switch blade, which will now be described. The switch blade 11 is constructed of suitable resilient conducting material and has a longitudinal opening 53 adjacent the center thereof for receiving the spindle 31. The forward end of the switch blade 11 is provided with a flanged head 55 adapted to engage the stationary contacts 7. The switch blade has a rearwardly extending portion 57 provided with a latch projection 59 which is adapted to be positioned in the notches 41 of the latch plate 9. A pair of spaced projections 60 extend upwardly from one edge of the switch blade 11 adjacent the slotted opening 53, and a second pair of similarly spaced projections 61 extend upwardly from the opposite edge of the switch blade 11 adjacent the slotted opening 53. The switch blade is mounted on the spindle by means of the slotted opening 53 and is held in spaced relation from the base 5 by means of a spacer washer 63. The slot 53 permits the blade 11 to have a limited sliding movement and to rotate for successive engagement with the spaced contacts 7.

Spring means 13 is coiled about the spindle and the free ends 65 thereof extend through the space between the projections 60 and 61, as shown in 55

Fig. 1. The normal tension of the spring causes its projecting ends 65 to engage the rearward projections 60 and 61, so as to bias the blade in a longitudinal direction to cause the latch projection 59 to engage in one of the notches 41 so as to lock the switch blade 11 whenever it engages any of the stationary contacts 7.

An operating member 15 of molded insulating material is rotatably mounted on the spindle 31 and is held thereon by means of a split ring 67 so that the spring 13 is compressed to press the switch blade 11 into engagement with the contacts 7 and to hold the blade against the spacer 63.

15 The operating member 15 is of segmental shape and has a hub portion 69 formed integral therewith on the under side thereof. The hub portion is provided with a centrally disposed opening 71 by means of which the operating member is rotatably mounted on the spindle 31. The centrally disposed opening 71 opens into a chamber 73 at the top of the operating member for receiving the split ring 67. The under side of the hub 69 has a semi-circular flange 75 formed integral therewith. One end of the flange 75 has a depending portion 77 adapted to engage the lower free end 65 of the coil spring 13 when the operating member is rotated in a counter-clockwise direction. The other end of the flange 75 is adapted to engage the upper free end 65 of the spring 13 when the operating member is rotated in a clockwise direction. A knob projection 79 is formed integral with the operating member adjacent the edge thereof by means of which the operating member may be manually rotated. The operating member may be constructed of any suitable insulating material.

The operation of the structure described above will now be briefly explained. Let it be assumed that it is desired to move the switch blade from the position shown in Fig. 1 into engagement with the next lower contact. It will be noted that in the position of the parts illustrated in Fig. 1 the ends of the spring 13 engage the rearward projections 60 and 61 to hold the latch projection 59 in one of the notches 41 so that the blade 11 is held in locked position on the center stationary contact 7. The operator grasps the knob 79 and rotates the operating member in a clockwise direction about the spindle 31. The upper end of the flange 75 (see Fig. 1) engages and moves the upper free end 65 of the spring 13 and introduces an additional tension in said spring. After a slight rotation of the operating member 15 in which sufficient tension is introduced in the spring means, the end of the flange causes the free upper end 65 of the spring to engage the forward projection 60. A slight additional rotation of the operating member causes the upper free end of the spring to move the forward projection 60 to slide the blade longitudinally in the forward direction so as to withdraw the latch projection 59 from its engagement in the notch 41. The switch blade is now free to rotate, and the increased tension of the spring causes the lower free end 65 to exert considerable force on the rear projection 61, thus causing the blade to rotate with a snap action, so as to engage the lowermost stationary contact 7. Further movement of the blade is prevented by reason of the lower free end 65 of the spring engaging the depending projection 77 of the flange 75 upon the operating member 15. At this time, the normal tension of the spring moves the blade longitudinally so that the latch projection

engages in the notch 41 corresponding to the lowermost contact. The blade is now securely locked in position on the lowermost contact 7. If it is desired to rotate the blade back to the position shown in Fig. 1 in which it engages the center stationary contact 7, the operating member is moved in a counter-clockwise direction and a reverse action takes place. The projection 77 of the flange 75 engages and moves the lower free end 65 of the spring 13 and introduces an additional tension therein. After the spring has been tensioned sufficiently, further movement causes the lower free end of the spring to engage the forward projection 61 and move the blade longitudinally to withdraw the latch projection 59 from the notch 41 in which it is engaged. The blade is now rotated with a snap action by the tension of the spring 13 into engagement with the center stationary contact 7. Further rotation of the switch blade 11 is prevented by reason of the upper free end 65 of the spring engaging the upper end of the flange 75. The normal tension of the spring 65 now moves the switch blade longitudinally so that the latch projection engages in the notch 41 corresponding to the center contact 7. It will be noted that the engagement of either end of the spring 13 with the forward projections of the pairs 60 and 61 causes sliding movement of the switch blade 11 so as to release the projection 59 from the notch in which it is engaged. The rearward projections of the pairs 60 and 61 form the means by which the blade is rotated by the tension of the spring 13, and in addition form the means whereby the normal tension of the spring causes longitudinal movement of the blade to latch engaging position.

It is evident without further explanation that if the operating member 15 is rotated far enough in either direction, the blade will be rotated in the manner described from contact to contact so that the amount of movement of the operating member 15 determines the amount of movement of the switch blade 11.

The normal or open circuit position of the switch blade 11 is that position in which it engages the terminal stud 45. If desired, however, an additional blank contact and a notch therefor in the latch plate (not shown) may be provided to be engaged by the switch blade in the normal or open circuit position thereof.

The number of stationary contacts and cooperating notches in the latch plate may be increased in number to meet the particular requirements. Only three have been illustrated in order to simplify the drawing.

The switch mechanism described herein may, for example, be employed to control the motor of an electric food mixing device, or may be employed to control any electrical device with which it is desirable or necessary to use a multi-contact switch having a snap action.

From the foregoing description, it is evident that the invention provides a novel form of snap switch in which a single spring serves to rotatably couple the switch blade with the manually controlled operating member, and also serves to lock or unlock the switch blade in or from engagement with any of the contacts. The spring also functions to rotate the blade with a snap action and presses the blade into engagement with the contacts.

While a particular embodiment of the invention has been shown, it is obvious that various changes may be made in the structure without

departing from the spirit of the invention. For example, the shape of the manually controlled operating member may be changed to suit particular requirements. A pair of depending projections of different length may be substituted for the semi-circular flange 15 and the depending projection 17. Likewise, various other means for coupling the spring to the operating member may be substituted for the specific coupling means illustrated. For example, the free ends of the spring may pass through slots in upwardly extending projection provided on opposite sides of the switch blade 11. Various other forms of spring means may be used in place of the coil spring illustrated. For example, a flat spring strip may be held in tension between the spindle 31 and the rearward projections on the switch blade.

While a preferred form of the invention has been illustrated, it is obvious that various changes and modifications, in addition to those suggested above, may be made without departing from the spirit of the invention as set forth in the following claims.

25 I claim as my invention:

1. A snap switch comprising a base provided with spaced contacts insulated therefrom, a spindle carried by said base, a latch plate carried by said base provided with spaced notches one 30 for each contact, a switch blade rotatably mounted on said spindle for cooperative engagement with said contacts, a latch piece carried by said blade for engagement in said notches, said blade having limited longitudinal movement, a pair 35 of spaced projections extending from each edge of said blade adjacent said spindle, a spring means held in tension between said spindle and two opposite projections for biasing said blade and latch piece longitudinally in a direction to engage said latch piece in said notches, an operating member rotatable on said spindle provided with projections on opposite sides of said spindle for engaging and moving either end of said spring means to further tension the same and for causing said spring means to engage and move either 40 of the remaining projections to move said blade longitudinally for withdrawing said latch piece from said notches when said spring has been tensioned sufficiently to rotate said blade with a snap action.

50 2. A snap switch comprising a base provided with spaced contacts and a latch plate having a plurality of spaced notches, a switch blade mounted on said base for rotation to successively engage said contacts and provided with a latch piece positionable in said notches to lock said blade in engagement with any of said contacts, said blade having limited longitudinal movement to permit withdrawal of said latch piece 55 from said notches, a spring means for rotating said blade and for normally biasing said blade to cause engagement of said latch piece in said notches, an operating member for further tensioning said spring means, said spring means when sufficiently tensioned to rotate said blade with a snap action engaging a means provided on said blade to move the same longitudinally to withdraw said latch piece from said notches to allow rotation of said blade.

70 3. In a switch mechanism, the combination of a base provided with spaced contacts and corresponding stops, a switch blade mounted on said base for limited sliding movement and for rotation to engage said contacts, a member carried by said blade for engagement with said stops

to lock said blade whenever it engages any of said contacts, spring means normally urging said blade in a longitudinal direction to cause said member to engage with said stops, and for rotating said blade, means for tensioning said spring means, and means carried by said blade engaged by said spring means when said spring means is sufficiently tensioned to rotate the blade with a snap action for moving said blade longitudinally to withdraw said member from the stop with 10 which it is engaged to free said blade for rotation by said spring means.

4. In a switch mechanism, the combination of a base provided with spaced contacts insulated therefrom and with corresponding spaced stops 15 one for each contact, a spindle, a switch blade mounted on said spindle for limited longitudinal movement and for rotation to successively engage said contacts, spaced projections carried by said blade at each side of said spindle, a member carried by said blade for engaging said stops to lock said blade on any one of said contacts, a spring means for rotating said blade, normally cooperating with said spindle and one pair of said projections for biasing said blade in a longitudinal direction to engage said member with said stops, an operating member having means for moving either end of said spring means to tension the same and for causing said spring means when it has been sufficiently tensioned to 20 engage one of the other pair of projections to move said blade longitudinally to withdraw said member from the stop with which it is engaged whereby said blade is freed for rotation by said spring means.

35 5. In a switch mechanism, the combination of spaced contacts, a spindle, a latch plate provided with spaced notches one for each contact, a switch blade mounted on said spindle for limited longitudinal movement and for rotation to engage said contacts, a member carried by said blade for engagement in said notches to lock said blade whenever it engages any one of said contacts, a pair of projections carried by the blade, spring means held in tension between said 40 spindle and said projections for normally urging said blade in a longitudinal direction to cause engagement of said member with said notches, and for rotating said blade when said spring means is tensioned, a second pair of projections carried by said blade adapted to be engaged by said spring means when sufficiently tensioned to cause said blade to move longitudinally to withdraw said member from the notch in which it is engaged, and operating means for tensioning said 45 spring means.

6. In a switch mechanism, the combination of a base provided with spaced contacts and with corresponding spaced stops, one for each contact, a spindle, a switch blade mounted on said spindle for limited longitudinal movement and for rotation to engage said contacts, a locking projection carried by said blade for engaging with said stops to lock said blade on any one of said contacts, spaced projections carried by said blade at each side of said spindle, a spring coiled about said spindle and having its ends disposed between the projections on each side of the spindle, said spring being normally held in tension between said spindle and two of said projections 55 so as to bias said blade in a longitudinal direction to engage said locking projection with said stops, a rotatable operating member having means for engaging and moving either end of said spring to further tension the same and cause 60

65 70 75

- said spring, when it has been sufficiently tensioned, to engage one of the other two projections to move said blade longitudinally and withdraw said locking projection from the stop with which it is engaged to cause said spring through the engagement of its other end with one of said first-mentioned two projections, to rotate said

blade with a snap action in the direction of rotation of said operating member, said means of said operating member limiting rotation of said blade an amount corresponding to the amount of rotation of said operating member.

CHRISTIAN AALBORG.
